UNITED STATES PATENT OFFICE

110,368

DESIGN FOR A CLEANING CABINET

Leslie E. Soderquist, Akron, Ohio, assignor to
National Rubber Machinery Co., Akron, Ohio, a
corporation of Ohio

Application November 8, 1937, Serial No. 72,706

Term of patent 7 years

To all whom it may concern:

Be it known that I, Leslie E. Soderquist, a citizen of the United States and a resident of Ohio, in the county of Summit and State of Ohio, have invented a new, original, and ornamental Design for Cleaning Cabinets, of which the following is a specification, reference being had to the accompanying drawing, forming part thereof.

The figure is a perspective view looking at the front of a cleaning cabinet embodying my new design. The back and both sides are substantially plain.

I claim:

The ornamental design for a cleaning cabinet, as shown and described.

LESLIE E. SODERQUIST.
